UNITED STATES PATENT OFFICE.

FRED M. MURAKOSHI, OF SAN LEANDRO, CALIFORNIA.

NAIL STRIPPER.

Application filed June 1, 1926. Serial No. 112,816.

The present invention relates to improvements in nail strippers, and has particular reference to a device which automatically arranges a bunch of nails dropped thereon in single files, so that the same may be withdrawn by the carpenter using the nails, to occupy the correct position between his fingers for immediate use.

The device is particularly intended for use by a carpenter nailing boxes, and is designed to stand alongside of the place where the carpenter works. One of the particular features of the device is that it is supported on slender brackets which cause the same to vibrate for advancing the nails into the correct position each time the carpenter strikes a blow with his hammer.

Further objects and advantages of my device will appear as the specification proceeds.

The preferred form of my invention is illustrated in the accompanying drawing in which—

Figure 1 shows a perspective view of my stripper set up for use;

Figure 2, a perspective view of a case in which the stripper may be enclosed, and

Figure 3, detail front and side views of one of the loops thru which the nails may be withdrawn, said front view being taken on line 3—3 of Figure 1.

While I have shown only the preferred form of the invention it should be understood that various changes or modifications may be made within the scope of the claims hereto attached, without departing from the spirit of the invention.

In its preferred form my stripper is preferably arranged in a case 1, of the form of a suit case, and preferably made of wood. The two halves 2 and 3 of the case are hinged as at 4 and provided with any suitable latch 5 for closing the same. From the bottom 6 of the case rise two standards 7 made of rather thin metal so as to readily yield to swinging motion. The lower ends 8 are fastened to the bottom by means of bolts and nuts 9 and the upper ends of the standards have a box 11 secured thereto in the manner shown in Figure 1, the ends of the brackets being secured to one wall of the box by means of bolts and nuts 12 in such a manner that the box slants downwardly from its support. The lowermost end of the box is open so that a bunch of nails thrown into the box will work downwardly, particu-

larly when the standards 7 are set into slight swinging or vibratory motion by the handling of a hammer in the immediate vicinity. As the nails advance over the lower edge of the box they drop upon the guide 13 which consists of a plurality of V-shaped troughs 14 with open bottoms so as to form slots allowing the shanks of the nails to drop therethrough, while preventing the heads from doing so. The troughs are arranged to slant downwardly from the lower end of the box in a reversed direction. The troughs communicate at their lower ends with sets of rods or rails 16 arranged so as to continue the slots in the troughs and to allow the heads of the nails to ride downwardly thereon. The upper end of the guide containing the troughs is secured to the lower end of the box by means of hooks 17, while the lower ends of the rods are fastened to a metal strip 18 which latter is adapted to be secured to the standards 7 by means of bolts and nuts 19, a thin plate 21 being preferably interposed between the strip 18 and the standards so as to form a partition in the case. In the rods an offset 22 is formed near the joint with the troughs, which offset consists of two laterally extending transverse loops 23, which provide a step in the rods and allow nails suspended from the rods to be withdrawn therethrough.

To somewhat strengthen the structure I connect the upper end of the box 11 to the bottom 6 of the case by means of a spring 24. To facilitate carrying of the device I place a strip 26 across the box 11 and fasten the ends thereof to the two halves of the case by means of cords 27 so that the whole device may be picked up by said strip.

To use the device the operator drops a bunch of nails on the box 11 and the nails will gradually slide downwardly, drop over the lower edge of the box on troughs 14 where they naturally arrange themselves in line formation with the shanks suspended from the heads and gradually the majority of the nails drop into the slot formed between the two rods 16. From this long line of nails thus suspended in the slots, the carpenter using the same may withdraw any number through the loops 23 and the nails will automatically be arranged between his fingers in parallel and upright position so that the carpenter may immediately proceed to place the nails successively and to immediately apply the hammer. The continuous

hammering in assembling boxes keeps my site end for supporting the box and formed 25 device in a vibratory or swinging motion to allow the box to slant downwardly from which aids the nails in arranging themselves. The supported end, the lower open end being in the proper relation. It will be seen that unsupported, a groove guide arranged relative to the lower end of the box so as to receive and arrange nails dropping therefrom and to guide the same downwardly, 30 and parallel guide rods communicating with the grooves allowing the heads of the nails to ride thereon while the shanks are suspended, the rods being looped at the joint 35 to allow a line of nails to be withdrawn thru the loops.

5 the device may be easily taken apart by disconnecting the cords 27, separating the guides by disengaging the hooks 17 and unscrewing the nuts 19, by disconnecting the box through loosening the nuts 12 and by 10 taking down the standards 7. The case 1 is sufficiently large to allow all the elements of the device to be assembled therein in such a manner that the casing may be closed as shown in Figure 2.

15 While the device is used a number of nails will be spilled, which gather on the bottom of the case and which may be caught in a receptacle placed on the bottom of the case to be dumped into the box 11 whenever desired by the operator.

I claim:—

1. A nail stripper of the character described, comprising a box open at one end thereof, elastic elements engaging the oppo-

2. A nail stripper as defined in claim 1 in which the grooved guide and the guide rods form one unit and are supported, at 40 opposite ends, by the elastic elements and the free end of the box.

3. A nail stripper as defined in claim 1 in which a spring engages the upper end of the box and is anchored to form an angle 45 with the elastic elements.

In testimony whereof I affix my signature.

FRED M. MURAKOSHI.
